BANK PROTECTIVE DEVICE

Charles A. Gilbert, Elkhart, Ind.

Application February 13, 1933. Serial No. 656,543

11 Claims. (Cl. 20—1.01)

This invention relates to protective devices for banks, and especially to devices for preventing bank robberies.

The principal object of this invention is to provide an improved device which not only protects the bank against robberies, but also prevents injury to the bank tellers.

Another object is to provide a protective device to enable a bank teller to quickly close the grated window of the teller's cage and to simultaneously screen the glass window located adjacent the grated window.

A third object of the invention is to provide a protective device to enable a bank teller to quickly close the grated window of his cage and to simultaneously close a door opening into said cage.

Yet another object of the invention is to provide a protective device for bank officials in which one or more movable shutters or doors are incorporated, one of the shutters being yieldable to compensate for obstructions interposed against the movement thereof.

Another object of the invention is to provide a bank protective device having a weight actuated shutter for closing the grated window of the teller's cage, and an electric motor for restoring the shutter actuating weight to an elevated position.

Other and more specific objects of the invention are mentioned and described herein.

My invention is illustrated in the accompanying drawings, wherein

Figure 1 is a perspective view of a bank teller's cage interior embodying my invention;

Fig. 2 is a vertical enlarged sectional view through one of the two trap units for actuating either one of the protective doors or shutters;

Fig. 3 is a plan view of one of the members of the trip mechanism incorporated in the trap units;

Fig. 4 is an enlarged fragmental view, in elevation, of the cage entrance door and the mechanism and devices for opening the door from both interior and exterior of the teller's cage;

Fig. 5 is a section taken on line 5—5 of Fig. 4;

Fig. 6 is a section taken on line 6—6 of Fig. 4;

Fig. 7 is a perspective view of the mechanism for unlocking the cage entrance door from the interior or exterior thereof;

Fig. 8 is a fragmental view in side elevation of the devices which disengageably connect the cage entrance door with the grated window shutter or door;

Fig. 9 is a view at right angles of the same elements;

Fig. 10 is an enlarged fragmental view of the grated window shutter or door, the window itself, the curtain connected with the shutter, and fragments of the shutter actuating devices;

Fig. 11 is a section taken on line 11—11 of Fig. 10;

Fig. 12 is a side elevational view of the electric motor and its mechanism for opening both doors to elevate the counter weights in the trap units, the same means being used to open the cage entrance door alone when it is disengaged from the grated window shutter;

Fig. 13 is an elevational view of the same devices; and

Fig. 14 is a view showing the locking device for the cables which actuate the door and window shutter.

Similar numerals of reference indicate like parts throughout the several views on the drawings.

Referring now to the details of the drawings the numeral 1 indicates the wall or partition of the teller's cage in which the usual grated window 2 is provided, with a desk 3 adjacent thereto. Numeral 4 indicates a movable shutter or door for closing the grated window 2, and numeral 5 indicates a spring roller curtain connected with the shutter 4 adjacent one edge of the latter for screening the glass or transparent window (not shown) located in the wall 1 behind the shutter 4 when the latter is retracted to disclose the window 2.

Numeral 6 indicates the teller's cage entrance door which is slidably mounted in the partition 1 in any suitable manner, but preferably on rollers, as herein described, said door being adapted to be actuated simultaneously with or independently of the shutter door 4, as herein-after described. The numeral 7 indicates a trap unit for actuating both the shutter 4 and the door 6 when the two are disengageably connected together, or the shutter door 4 alone when the door 6 is closed and the former is to be closed over the window 2. Numeral 8 indicates the second trap unit which is adapted to close only the door 6 independently of the shutter door 4. Both of the trap units 7 and 8 are alike in mechanical details and only one of them will be described herein for that reason.

The numeral 9 indicates the cable for actuating the shutter door 4 and which is connected with the latter at 10, said cable being trained over suitable rollers or pulleys 11 and 12 to connect the end thereof with the counter weight 13, the latter being arranged within the trap unit 7, or

8, the latter including a suitable apertured casting to admit the cable 9 thereto. The numeral 14 indicates a flexible cable for closing the door 6 and it is connected with said door at 15 and 5 trained over the pulleys or rollers 16, 17 and 18, thence into the trap unit 8 where it is connected with a counter weight 13 in said unit. The roller 16 is mounted on the partition 1 ahead of the cable anchorage 15 to effect the necessary draft 10 on the door for closing the latter which follows the fall of the weight 13 in the trap unit.

The shutter 4 is carried upon the roller trucks 19 and 19' which operate upon the horizontal double track bars 20 and 21 which have their 15 extremities mounted in the brackets 22 and 23 carried by the partition 1, and the door 6 is operable upon said track bars by roller trucks 24 and 25. Both the shutter 4 and door 6 are arranged between the track bars 20 and 21 which are sufficiently close together to maintain the juxtaposition of the members 4 and 6 there-between. Preferably, the track bars 20 and 21 are made of flat metal to facilitate the engagement of the roller trucks 19, 19' and 24 and 25 therewith.

20 The numeral 26 indicates a horizontal abutment bar connected with the partition 1 and arranged in front of the shutter 4 and grated window 2 to prevent unauthorized inward tiltable displacement of the shutter 4 in either the open or closed position thereof.

The numerals 27 and 28 indicate two pairs of abutment rollers suitably mounted in the shutter door 4 below the track bars 20 and 21 and spaced therefrom suitably to admit of limited upward displacement of the shutter 4 and rollers 19 and 19', said rollers being adapted to engage the under side of the track bars when the shutter is upwardly displaced for any reason, as by an obstruction beneath said shutter when the latter is in motion. Similarly, the door 6 is provided with a pair of abutment rollers 29 and 30 below and spaced from the track bars 20 and 21 and which are adapted to engage said tracks upon upward displacement of the door 6 and to function as stop elements.

45 Numeral 31 indicates a traction bar disengageably connecting the shutter door 4 with door 6 and rigidly connected with the former at 32. The outer end of the traction bar 31 carries an enlarged head or knob 33 which is engageable with a furcated abutment member 34 fixedly connected with the top end of the door 6, said bar being displaceable upward out of engagement with the furcation of the member 34 to release the door 6 from the bar knob 33 to enable independent movement of said door. When the bar 31 is thus displaced from the member 34 it is caused to engage the furcation 35 of the furcated member or bracket 36 which is positioned above the member 34 and rigid with partition 1, whereby the knob 33 is caused to engage the face of member 36 disengageably locking the shutter 4 against closure movement, as is hereinafter described.

60 The numeral 37 indicates a yieldably mounted wall section of the partition 1 and arranged between the track bars 20 and 21, the upper end whereof is carried upon the two pairs of roller trucks 38 and 39 which operate upon said track bars similar to the function of rollers 24 and 25 of door 6.

70 The partition wall section 37 carries also the abutment rollers 40 and 41 below and spaced from the track bars 20 and 21 which function to engage said track bars to limit upward movement of the

80 wall section 37 when the latter may be upwardly displaced for any reason. The numerals 42 and 43 indicate compression springs which encompass the carrier and guide rods 44 and 45, respectively, which are rigidly connected with the wall section 37, said rods having their ends slidably and tiltably engaging in suitable apertures 48 formed in the guide brackets 46 and 47, respectively, rigid with the partition 1. The wall section 37 is adapted to function as a yieldable abutment for the door 6 when the latter is closed upon any kind of an obstruction of limited volume interposed between the edges of said door and said wall section.

85 Means for positively locking the wall section 37 against yielding movement is provided and may comprise a bell-crank 49 tiltably mounted on said wall section at 50, a vertically arranged and slidable locking bolt 51 connected with one arm of said bell-crank, and a bell-crank actuating pin 52 which is slidably and horizontally arranged in the guide bracket 53, the point of said pin being engageable by a hammer block 54 rigidly mounted on door 6 adjacent the edge thereof. Normally, the point of the locking bolt 51 is disengaged from a bolt socket 55 formed in track bar 20, and will drop from said socket when subject to no urge, said bolt being forced into said bolt socket only when the block 54 forcibly engages the point of the pin 52, the latter being 100 operatively connected with the second arm of the bell-crank 49.

90 In the event an obstruction is interposed, for any reason, between door 6 and wall section 37, when the former is forcibly closed, or actuated 110 for closure, it then becomes impossible for the hammer block 54 to engage or actuate the pin 52, whereby the said wall section will yield to the right against the springs 42 and 43, as indicated 115 in dotted lines thereof. If the obstruction referred to were a man's hand or arm serious injury thereto would thereby be averted.

95 As heretofore stated the trap units 7 and 8 are alike in mechanical details and only one of them will therefore be described. Numeral 56 indicates the trap unit casing within which the counter weight 13 disposed for operation when connected with the cable 9. When elevated, the weight 13 is supported upon the inner end of a supporting lever 57 which is pivotally mounted 120 in a pair of opposed bearing brackets 58 and 59 exteriorly of the casing 56, said supporting lever being held in a normally horizontal position by a trigger element 60 which is disengageably locked thereto by a notch element 61, said 125 trigger element being pivotally mounted on a shaft 62 which is carried in the brackets 58 and 59. The supporting lever 57 may be provided with opposed trunnion pins 63 and 64 (Fig. 3) 130 to provide the desired pivotal support therefor 135 in the brackets 58 and 59.

100 The inner end of the lever 57, upon which the weight 13 normally is carried, may be furcated at 66 with a roller 67 mounted in said furcation, the opposite end of said lever projecting through 140 an opening 65 formed in the wall of the casing 56. Numeral 68 indicates a curved pick-up arm secured to the bottom of the weight 13 by screws, or otherwise suitably by fastener members 69, said curved arm being arranged within the lever 145 furcation 66, the point thereof extending beyond the roller 67 toward the medial portion of said lever and in contact with the roller 67.

105 The numeral 70 indicates a link operatively connecting the upper end of the trigger 60 with 150

the lever 71 which is rigid with a rock shaft 72 mounted in brackets 73 and 74 in casing 56, said rock shaft carrying also a lever 75 on the outer end thereof. A link 76 operatively connects the lever 75 with a lever 77 mounted upon a horizontal rock-shaft 78 carried in suitable bearing brackets 79, said rock shaft having a foot pedal 80 mounted thereon to rock said shaft. Obviously, when pedal 80 is depressed, the trigger 10 60 is tilted away from the casing 56, thereby disengaging the notch 61 from the point of the supporting lever 51, thereby releasing the weight 13 of trigger control and causing said weight to fall to the bottom of the casing 56, whereby 15 shutter 4 is actuated and window 2 closed thereby. Simultaneously the curtain 5 is caused to be unrolled and to screen the glass window exposed by the closure movement of said shutter 4. The fall of the weight 13 tilts the supporting lever 57 20 to an upright position and the weight of the parts causes the trigger 60 to tilt toward the casing 56 to an inclined position and leaning against the upper end of the lever 57, in which relation the parts are at rest. Upon elevation 25 of the weight 13 by the electric motor, or otherwise, as hereinafter described, the point of the weight arm 68, which projects through casing opening 65, engages, or picks-up the roller 67 in the lever furcation 66, continued elevation of 30 said weight tilting the lever 57 to a horizontal position and causing the outer end of said lever to again engage the notch 61 of trigger 60 which has been tilted outward by said lever. In such movement of the parts described the inner end 35 of the lever 57 again functions as a support for the weight 13, as is apparent, which is then releasably locked thereon.

The elevation of the weight 13, as described, also rocks shafts 72 and 78, and the levers and members carried thereby, to their former positions, whereby depression of the pedal 80 will again cause the fall of the weight 13 with the results as described. From the foregoing it will be evident, if the door 6 is open and rod 31 is operatively connected therewith by bracket 34 and knob 33, that the fall of the weight 13 will not only actuate shutter 4 and curtain 5 but also effect closure movement of the door 6. And it will also be evident, if the door 6 is closed on that occasion, that the fall of the weight 13 will have no effect on said door. Furthermore, if the knob 33 of rod 31 has been shifted into engagement with bracket 36, as hereinbefore described, the shutter 4 will be locked thereby against closure movement.

Means is provided to facilitate the closure of the shutter door 4 against ordinary obstructions, and the successful operation of such means contemplates the rounding of the corner 81 of said shutter, whereby when said shutter is closed, or during its closure movement, upward displacement of the shutter will occur when it contacts with any such obstruction which may be thrust through the grated window 2 adjacent the desk 3, and whereby the shutter 4 will glide over such obstruction and fully close said window. And in any such upward displacement of the shutter door 4 the roller trucks 27 and 28 will limit the upward movement of said shutter door. In the event any ordinary obstruction is interposed below the door 6 the rollers 29 and 30 will admit of limited upward displacement of said door, enabling the full and complete closure of said door. And similarly, rollers 40 and 41 will admit of limited upward displacement of the wall section 37.

The trap unit 8 may be operated in any suitable

manner to release the weight 13 therein for closing the door 6, but, as illustrated, a lever arm 84 is utilized for that purpose, said lever being rigidly connected with the rock-shaft 72 in said trap unit, as a substitute for the lever 75 shown in Fig. 2 of trap unit 7, and when the lever 84 is swung upward by the operator the weight 13 is thereby released and actuation of the door 6 follows such release.

Motor means is provided for opening shutter 4 and door 6, and such means may take the form of an electric motor 85 mounted on a suitable bracket 86, the motor drive shaft carrying a spur gear 87 which meshes with a spur gear 88, the latter being carried on a bearing pin 89 projecting from a lever arm 90, said lever arm being pivotally carried at 91 in a bracket 92 supported on the motor bracket 87. The lever arm 90 is provided with a handle 93 projecting laterally therefrom, whereby the gear 88 may be manually swung upward and downward and into and out of mesh with a toothed rack element 94 which is provided on the horizontal door actuating bar 95, the latter having one end thereof rigidly connected with the door 6. The bar 95 carries also a depending knock-off cam 96 which is adapted to engage the gear 88 to demesh 100 same from the rack 94 when the door 6 and shutter 4 have been fully opened and both weights 13 in units 7 and 8 have been elevated and latched in position. Normally, the gear 88 is disengaged from the rack 94 by the weight of the handle 93.

When desirable, the cables 9 and 14 may be locked against movement even though the weights 13 may be free to fall, such locking devices comprising a locking box 97 for each cable, which box is traversed by the cable which is normally free 110 to move therethrough, in either direction.

Each of the cable locking boxes 97 is provided with an L shaped locking lever 98 pivotally mounted therein at 99, the lower end or point 100 whereof may be swung into and out of engagement 115 with the cable, at the will of an operator, whereby, when so engaged with the cable, draft on said cable, which would tend to close the door 6 and shutter 4, causes the point 100 to force the cable against the wall of the box 97 and locking the cable 120 rigidly against draft.

Mechanism is provided for opening the door 6 independently of shutter 4 and from either the interior or exterior of the teller's cage. Such a means contemplates a lever 101 which is pivotally 125 mounted in a floor bracket or bearing 102 intermediate the lever extremities, the bracket 102 being mounted within the teller's cage, preferably, and said lever being provided with a lateral pedal 103 which projects through a 130 suitable opening in the partition 1 to the exterior of the cage. As heretofore stated, the door actuating bar 31 is provided with a knob 33 which normally engages the furcated bracket 34 on door 6. And it has also been shown that the 135 bar 31 is movable upward to cause the disengagement of the bar knob 33 from the bracket 34, and such upward displacement of the bar 31 is effected by a forked lever 104 mounted on the rock-shaft 105, said bar 31 traversing the furcation of said 140 forked lever, and said rock shaft being mounted in suitable brackets 106 and 107 and rockable by a lever 108 and a link 109, the latter operatively connecting the pedal lever 101 with the rock shaft lever 108. Obviously, depression of the pedal 103, 145 positioned outside of the partition 1, will rock the shaft 105 and disengage the bar 31 from bracket 34 and elevate said bar into the furcation 35 of the bracket 36, thereby releasing the door 6 from the abutment knob 33. The same effect may be pro- 150

vided or produced by actuation of the lever 101 which is accessible adjacent the point of connection with the link 109.

I claim:

5. 1. In a device of the character described and in combination with a pair of windows positioned adjacent each other in a partition, a movable shutter, a flexible curtain connected therewith, and means for actuating said shutter to close 10 one of said windows, whereby said curtain is caused to screen the other window. 80
15. 2. In a device of the character described and in combination with a partition provided with a pair of windows, one of said windows being grated, a movable shutter, a spring roller curtain connected therewith, and means for actuating said shutter to close said grated window, whereby 90 said curtain is caused to screen the other window. 85
20. 3. In a device of the character described and in combination with a partition provided with a grated opening or window, a movable shutter disposed adjacent said window, means for actuating said shutter to close said window, and means enabling upward displacement of the shutter to 100 overlie an obstruction. 95
25. 4. In a device of the character described and in combination with a partition provided with a window, a track, a shutter movably mounted on said track, means for actuating said shutter to close said window, and means enabling upward displacement of the shutter to override an obstruction, said means including roller means carried by the shutter and arranged below said track. 105
30. 5. In a device of the character described and in combination with a partition provided with a window, a track, a shutter movably mounted on said track, means for actuating said shutter to close said window, said shutter being upwardly 110 displaceable from said track, and means carried by said shutter for limiting the upward displacement of said shutter. 115
35. 6. In a device of the character described and in combination with a partition provided with a window, a track, a shutter provided with rollers and movably mounted on said track, said shutter being upwardly displaceable from said track, means for limiting the upward displacement of said shutter, and means for actuating said shutter to close said window. 120
40. 7. In a device of the character described and in combination with a partition provided with a window and an entrance, a sliding door adapted to close said partition entrance, a movable shutter, means for actuating said shutter to 125 close said window, means connecting said door and shutter to enable simultaneous actuation thereof, yieldable abutment means for said door, and means for positively locking said abutment means. 130
